UNITED STATES PATENT OFFICE.

WILLIAM C. GILMORE, OF WACO, TEXAS.

GAS GENERATOR.

Application filed November 7, 1924. Serial No. 748,460.

To all whom it may concern:

Be it known that I, WILLIAM C. GILMORE, a citizen of the United States, residing at Waco, in the county of McLennan and State 5 of Texas, have invented new and useful Improvements in Gas Generators, of which the following is a specification.

This invention relates to an improved generator for acetylene gas, the general object 10 of the invention being to provide automatic means for controlling the feeding of the carbide by the movement of the gas bell.

Another object of the invention is to provide balanced spring means for holding the 15 feeding valve for the carbide upon its seat and also to provide a bridge for keeping the weight of the carbide off the valve.

A further object of the invention is to provide protective casings for the spring 20 means and the valve stems to prevent anything from interfering with the operation of the valve.

A still further object is to make the valve 25 of such a form as to insure its proper closing and also to provide a protective hood for the inlet end of the gas pipe.

This invention also consists in certain other features of construction and in the 30 combination and arrangement of the several parts, to be hereinafter fully described, illustrated in the accompanying drawings and specifically pointed out in the appended claims.

In describing my invention in detail, reference will be had to the accompanying 35 drawings wherein like characters denote like or corresponding parts throughout the several views, and in which:—

Figure 1 is an elevation of the invention. 40 Figure 2 is a longitudinal sectional view thereof.

Figure 3 is a plan view.

Figure 4 is an enlarged sectional view 45 showing the means for controlling the feed of carbide.

Figure 5 is a section on line 5—5 of Figure 4.

Figure 6 is a section on line 6—6 of Figure 4.

50 In these views 1 indicates the base of the device which is to contain the water for the generation of the gas and 2 indicates the reduced extension which is connected with part 1 by the flaring central part 3. A part 55 4 surrounds the part 2 and has its lower end secured to the central part 3, the walls of

parts 2 and 4 forming a water chamber 5 which acts as a seal for the bell 6, this bell enclosing the upper portion of part 2. I prefer to make these parts of hexagon shape, 60 as shown in the drawings, so that the pipe connections may be easily made on flat sides.

The hopper 7, also of hexagon shape, is suspended in the upper portion of part 2 by means of the hook shaped brackets 8, said 65 hopper having a tapered bottom with an opening 9 therein, the end walls of the opening being of inverted V-shape. An inverted

V-shaped plate 10 extends across the lower part of the hopper above the opening, as 70 shown. This opening is closed by the valve 11 which is also of inverted V-shape in cross section so as to tightly close the opening, this valve being carried by the U-shaped rod 75

12, the limbs of which extend through the vertically arranged tubes 13 passing through the hopper and the bight of said U-shaped rod carrying the valve. The upper ends of 80

said rod extend above the hopper and the tubes 13 so that they will be engaged by the bell when the same is in its lower position. A pair of tubes 14 is located in the hopper, 85

the upper ends of said tubes being closed while the lower ends are open. Coil springs 15 are arranged in said tubes and these 85

springs are connected with the bight of rod 12 and their upper ends are secured to eye bolts 16 which engage nuts 17 on the tops of the tubes 14. By means of these nuts and 90

eye bolts the tension of the springs may be adjusted. These springs will hold the valve 95

11 upon its seat but the weight of the bell 2 upon the ends of said rod 12 will push the rod and the valve downwardly against the action of the springs so as to move the valve 95

off its seat and permit some of the carbide to drop through opening 9 into the water in the base and thus generate gas which will rise in part 2 and into the bell thus raising 100

said bell and permitting the springs to seat the valve 11 and thus cut off the supply of carbide. The plate 10 will prevent the

weight of the carbide in the hopper from interfering with the working of the valve 105

and the tubes enclosing the limbs of rod 12 and the springs will prevent carbide or anything else from interfering with the proper working of these parts.

The gas pipe 18 passes through one side 110 of part 1 and a cylindrical pipe 19 is connected with the interior part of the pipe and has its upper end located in part 2. A

perforated hood 20 encloses said upper end, this hood acting to permit the gas to pass into the pipes 19 and 18 but preventing pieces of carbide and water from entering these pipes. The outer end of pipe 18 is coupled to the pipe 21 which leads the gas to the filter 22, this filter being connected with the piping system of the house by pipe 23. A valve 24 is located adjacent the junction of pipe 21 with the filter. The base 1 is also provided with a drain pipe 25.

From the foregoing it will be apparent that the carbide will be automatically fed into the water to generate gas by the action of the gas bell and as soon as the gas is generated the valve is closed, thus keeping the supply of gas constant. The springs will balance each other so as to make the feed of carbide substantially the same at each operation. The valve springs and stem are protected by the small casings or tubes and the shape of the valve and its seat causes it to close perfectly, thereby avoiding any leakage of carbide. The springs can be adjusted to control the movement of the valve and the bridge prevents the weight of the carbide from interfering with the movement of the valve.

It is thought from the foregoing description that the advantages and novel features of my invention will be readily apparent.

I desire it to be understood that I may make changes in the construction and in the combination and arrangement of the several

parts, provided that such changes fall within the scope of the appended claims.

What I claim is:—

1. A gas generator of the class described comprising a casing having a water chamber in its lower part, a hopper in its upper part, a water chamber surrounding the said upper part, a bell in said chamber, a valve controlling the outlet of the hopper, a U-shaped rod carrying the valve, the limbs of the U extending above the top of the hopper and adapted to be engaged by the bell, a pair of springs, one on each side of the valve and connected with the bight of the U for holding the valve upon its seat and an outlet pipe connected with the casing for leading the gas from the casing.

2. A gas generator of the class described comprising a casing having a water chamber in its lower part, a hopper suspended in the chamber part, a water chamber surrounding the said upper part, a bell in said chamber, a valve for controlling the outlet of the hopper, a U-shaped rod carrying said valve and having its limbs passing through the hopper and arranged to be engaged by the bell, tubes surrounding said limbs, a pair of springs connected with the bight of the U, one on each side of the valve, tubes surrounding said springs, means for adjusting the tension of the springs and a gas discharge pipe connected with the casing.

In testimony whereof I affix my signature.

WILLIAM C. GILMORE.
